CLAIM

The ornamental design for a beverage container, as shown and described.

DESCRIPTION

FIG. 1 a perspective view of a first embodiment of our new design for a beverage container;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of our new design for a beverage container;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines showing in the figures are included for the purpose of illustrating portions of the beverage container that form no part of the claimed design. The dash-dot lines showing in the figures are included for defining the bounds of the claimed design that form no part thereof. The second embodiment of a beverage container is shown with a symbolic break in its length. The appearance of any portion of the article between the break lines forms no part of the claimed design.
